(57) **CLAIM**

The ornamental design for an automatic pistol recoil simulator, as shown and described.

DESCRIPTION

FIG. 1 is a perspective view of an automatic pistol recoil simulator according to my novel design;

FIG. 2 is a front elevation view, thereof;

FIG. 3 is a right side elevation view, thereof;

FIG. 4 is a rear elevation view, thereof;

FIG. 5 is a left side elevation view, thereof;

FIG. 6 is an end view, thereof; and,

FIG. 7 is an opposing end view, thereof.

The larger cylindrical portion of the automatic pistol recoil simulator is translucent, and the smaller cylindrical portion is transparent.
